(57) **CLAIM**

The ornamental design for a wearable sports instrumentation display, as shown and described.

DESCRIPTION

FIG. 1 is a top plan view of a wearable sports instrument display showing our new design;

FIG. 2 is a front elevational view thereof;

FIG. 3 is a side elevational view thereof;

FIG. 4 is a bottom plan view thereof;

FIG. 5 is a top perspective view thereof; and,

FIG. 6 is a bottom perspective view thereof.

The broken lines in FIGS. 1 and 5 indicate the environment and form no part of the claimed design.
